UNITED STATES PATENT OFFICE.

WILLOUGHBY M. McCORMICK, OF BALTIMORE, MARYLAND.

DESIGN FOR A BOTTLE.

SPECIFICATION forming part of Design No. 35,976, dated July 8, 1902.

Application filed June 5, 1902. Serial No. 110,392. Term of patent 7 years.

To all whom it may concern:

Be it known that I, WILLOUGHBY M. McCORMICK, a citizen of the United States, residing at Baltimore, in the State of Maryland, have invented and produced a new and original ornamental Design for Bottles, of which the following is a specification, reference being had to the accompanying drawings, forming part thereof, in which—

Figure 1 is a perspective view of a bottle, showing my new design. Fig. 2 is a side view and Fig. 3 a top plan view thereof.

As shown in the drawings, the leading or material feature of my design consists of a bottle having three equilaterals sides A, so that the bottle is triangular in cross-section, and on one of the flat sides of the bottle is an ornamental scroll C, imitating a belt and inclosing an image of a bee blown in the side of

the bottle. The two other sides of the bottle are plain. The bottle also has a cylindrical neck B of such diameter that when viewed from one side, as in Fig. 2, or from the top, as in Fig. 1, the periphery of the neck is flush or in line with the adjacent side, the angles formed by the sides being rounded and sloping toward the neck, as shown.

Having thus described my invention, what I therefore claim as new is—

The ornamental design for a bottle herein shown and described.

In testimony whereof I have signed my name to this specification in the presence of two subscribing witnesses.

WILLOUGHBY M. McCORMICK.

In presence of—

WM. H. H. RALEIGH,
LOUIS W. RHODRICK.
